US00D599127S

(12) **United States Design Patent**
Smith

(10) **Patent No.:** **US D599,127 S**
(45) **Date of Patent:** **** Sep. 1, 2009**

(54) **MESH FOLDING CHAIR**(75) Inventor: **Richard D. Smith**, Spanish Fork, UT (US)(73) Assignee: **Mity-Lite, Inc.**, Orem, UT (US)(**) Term: **14 Years**(21) Appl. No.: **29/335,295**(22) Filed: **Apr. 13, 2009**(51) **LOC (9) Cl.** **06-01**(52) **U.S. Cl.** **D6/368**(58) **Field of Classification Search** **D6/334-336, D6/368, 369, 370, 374, 376, 379, 380, 500-502; 297/16.1, 40, 41, 55, 56, 58, 452.13, 452.21, 297/452.29, 452.64**

See application file for complete search history.

(57) **CLAIM**

The ornamental design for the mesh folding chair, as shown and described.

DESCRIPTION

FIG. 1 is a front perspective view of the mesh folding chair in accordance with my invention;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in FIGS. 1-7 are for illustrative purposes only and form no part of the claimed design.
